UNITED STATES PATENT OFFICE.

HOWARD M. BARBER, OF STONINGTON, CONNECTICUT, ASSIGNOR TO C. B. COTTRELL & SONS COMPANY, OF NEW YORK, N. Y., A CORPORATION OF DELAWARE.

INKING MECHANISM FOR PRINTING PRESSES.

Application filed May 26, 1923. Serial No. 641,771.

To all whom it may concern:

Be it known that I, HOWARD M. BARBER, a citizen of the United States, and resident of Stonington, in the county of New London and State of Connecticut, have invented 5 a new and useful Improvement in Inking Mechanism for Printing Presses, of which the following is a specification.

In the old method of adjusting the composition rollers of inking mechanisms, it is necessary to use a wrench at right angles to the adjusting screw in between the roller frames and the ends of the various inking rollers and cylinders. In many places it is 15 very difficult, if not impossible, to operate the wrench in the space around the socket and this is especially true where a roller washing device is employed, as practically all of the space between the ends of the various inking rollers and cylinders and the roller frame is occupied.

The object of my invention is to overcome the difficulties above enumerated by providing novel means for radially adjusting 23 the composition rollers, said means including manually operated adjusting shafts carried by the roller socket members with the head ends of the shafts arranged in convenient position for action with the wrench or 30 other operating tool.

A practical embodiment of my invention is represented in the accompanying drawings, in which—

Fig. 1 represents a portion of an inking 35 mechanism in side elevation, with my improvement applied thereto.

Fig. 2 represents a detail top plan view of the same, showing my improvement applied to both ends of the composition roller shafts.

Fig. 3 represents a detail section taken in 40 the planes of the line III—III of Fig. 2.

Fig. 4 represents a detail section taken in the plane of the line IV—IV of Fig. 1.

The usual roller frames of the machine are 45 denoted by 1 and 2. The ink transfer rollers illustrated herein are denoted by 3, 4 and 5, the rollers 3 and 5 being the composition rollers and the roller 4 being an interposed iron roller. The means for adjusting the 50 position of each of the composition rollers, in the present instance, is constructed, arranged and operated as follows, it being understood that a separate means is provided for each end of each of the composition roller 55 shafts.

The bearing member 6 for the reduced end of the roller shaft 7 is provided with a stem 8 having a screw-threaded longitudinal bore 9.

The roller bearing socket member 10 is 60 secured to its side frame 1 or 2 by the usual bolt 11.

This socket member has a longitudinal bore 12, arranged to slidably receive the stem 8 of the roller bearing member 6, the 65 said roller bearing member being prevented from turning by providing the stem with a longitudinal exterior groove 13 and the socket member with a pin 14 extending into said groove.

A stud 15 is rotatably mounted in the socket member 10 and its shank 16 is screw-threaded into the bore 9 of the stem 8 of the bearing member, so that the turning of the stud will move the bearing member longitudinally with respect to the socket member.

The socket member 10 is also provided with another longitudinal bore 17 within which is rotatably mounted the manually 80 operated adjusting shaft 18, which shaft at one end is provided with a gear 19 meshing with a gear 20, fast on the corresponding end of the rotary stud 15. The other end of the adjusting shaft 18 is shaped to receive any suitable tool for manually rotating the shaft. In the present instance it is provided with a squared end 21 for receiving the socket of a wrench of well known or approved form (not shown herein).

Means are provided for holding the roller bearing member in its adjusted position, which means in the present instance is shown as engaging the adjusting shaft 18 and comprises a spring pressed pawl 22 seated in a 95 recess 23 in the socket member 10, the exposed end of which pawl engages a ratchet 24 fast on the adjusting shaft.

From the above description it will be seen that each roller bearing member may 100 be adjusted to a nicety by rotating the adjusting shaft in the one or the other direction and, when the proper adjustment has been obtained, it will be maintained by the pawl and ratchet connection 22, 24. The 105 adjusting shaft is preferably inclined with respect to the rotary stud and roller bearing stem, this arrangement permitting the use of small connecting gears between the shaft and stud and bringing the head end of the 110

shaft which is to be connected to the operating tool in proximity to but out of line with the enlarged portion of the roller bearing member and thus facilitating the ready operation of the adjusting shaft. A suitable tool for turning the adjusting shaft would be a socket wrench with a universal joint so that the handle of the wrench could be positioned outside the roller frame for ready manipulation.

It is evident that various changes may be resorted to in the construction, form and arrangement of the several parts without departing from the spirit and scope of my invention; hence, I do not wish to be limited to the particular embodiment herein shown and described, but—

What I claim is:

1. An ink transfer roller, and means for adjusting the position of the roller comprising, a bearing member for each end of the roller, a radially disposed stud having a screw-threaded engagement with the bearing member, and a manually operated adjusting shaft located along the side of said stud and geared at its outer end to the outer end of said stud, the inner end of said adjusting shaft being arranged to be engaged by a tool for turning the shaft to move the bearing member to its desired position.

2. An ink transfer roller, and means for adjusting the position of the roller comprising, a bearing member for each end of the roller, a radially disposed stud having a screw-threaded engagement with the bearing member, a manually operated adjusting shaft located along the side of said stud and geared at its outer end to the outer end of said stud, the inner end of said adjusting shaft being arranged to be engaged by a tool for turning the shaft to move the bearing member to its desired position, and means for holding the bearing member in its adjusted position.

3. An ink transfer roller, and means for adjusting the position of the roller comprising, a bearing member for each end of the roller, a radially disposed stud having a screw-threaded engagement with the bearing member, a manually operated adjusting shaft located along the side of said stud and geared at its outer end to the outer end of said stud, the inner end of the adjusting shaft being arranged to be engaged by a tool for turning the shaft to move the bearing member to its desired position, and means engaging the adjusting shaft for holding the bearing member in its adjusted position.

4. An ink transfer roller, and means for adjusting the position of the roller comprising, a bearing member for each end of the roller, a fixed socket member carrying the roller bearing member, said roller bearing member having a radially disposed stem

slidable in the socket member, a radially disposed rotary stud mounted in the socket member and having a screw-threaded engagement with said stem, and a manually operated adjusting shaft mounted in said socket member along the side of said stud and geared at its outer end to the outer end of said stud, the inner end of said adjusting shaft being arranged to be engaged by a tool for turning the shaft to move the bearing member to its desired position.

5. An ink transfer roller, and means for adjusting the position of the roller comprising, a bearing member for each end of the roller, a fixed socket member carrying the roller bearing member, said roller bearing member having a radially disposed stem slidable in the socket member, a radially disposed rotary stud mounted in the socket member and having a screw-threaded engagement with said stem, a manually operated adjusting shaft mounted in said socket member along the side of said stud and geared at its outer end to the outer end of said stud, the inner end of said adjusting shaft being arranged to be engaged by a tool, for turning the shaft to move the bearing member to its desired position, and means for holding the bearing member in its adjusted position.

6. An ink transfer roller, and means for adjusting the position of the roller comprising, a bearing member for each end of the roller, a fixed socket member carrying the roller bearing member, said roller bearing member having a radially disposed stem slidable in the socket member, a radially disposed rotary stud mounted in the socket member and having a screw-threaded engagement with said stem, a manually operated adjusting shaft mounted in said socket member along the side of said stud and geared at its outer end to the outer end of said stud, the inner end of said adjusting shaft being arranged to be engaged by a tool for turning the shaft to move the bearing member to its desired position, and means for holding the bearing member in its adjusted position.

7. An ink transfer roller, and means for adjusting the position of the roller comprising, a roller bearing member having a radially disposed stem, a manually operated adjusting shaft, a fixed socket member carrying the roller bearing member and having two longitudinal bores located side by side, one for slidably receiving the bearing member stem and the other for rotatively mounting the adjusting shaft, and a radially disposed stud rotatably mounted in the socket member, said stud being geared at its outer end to the outer end of the adjusting shaft and screw-threaded into said bearing member stem, the inner end of the adjusting

- shaft being arranged to be engaged by a tool whereby the bearing member may be moved to the desired position by the manipulation of the adjusting shaft.
- 5 8. An ink transfer roller, and means for adjusting the position of the roller comprising, a roller bearing member having a radially disposed stem, a manually operated adjusting shaft, a fixed socket member 10 carrying the roller bearing member and having two longitudinal bores located side by side, one for slidably receiving the bearing member stem and the other for rotatively mounting the adjusting shaft, a radially disposed stud rotatably mounted in the socket member, said stud being geared at its outer end to the outer end of the adjusting shaft and screw-threaded into said bearing member stem, the inner end of the adjusting 15 shaft being arranged to be engaged by a tool whereby the bearing member may be moved to the desired position by the manipulation of the adjusting shaft, and means for holding the bearing member in its adjusted position.
- 20 25 9. An ink transfer roller, and means for adjusting the position of the roller comprising, a roller bearing member having a radially disposed stem, a manually operated adjusting shaft, a fixed socket member 30 carrying the roller bearing member and having two longitudinal bores located side by side, one for slidably receiving the bearing member stem and the other for rotatively mounting the adjusting shaft, a radially disposed stud rotatably mounted in the socket member, said stud being geared at its outer end to the outer end of the adjusting shaft and screw-threaded into said bearing member stem, the inner end of the adjusting 35 shaft being arranged to be engaged by a tool, whereby the bearing member may be moved to the desired position by the manipulation of the adjusting shaft, and means engaging the adjusting shaft for holding the bearing member in its adjusted position.
- 40 In testimony, that I claim the foregoing as my invention, I have signed my name this 23rd day of May 1923.
- 45 HOWARD M. BARBER.
